UNITED STATES PATENT OFFICE.

CARL J. PRACHT, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TRUNK-SELECTING SWITCH FOR TELEPHONE SYSTEMS.

Application filed June 16, 1922, Serial No. 568,694. Renewed September 23, 1926.

The present invention relates to trunk selecting switches for telephone systems, but is more particularly concerned with the production of a secondary trunk selecting switch in which the usual switch mechanism is eliminated and relays are employed to select an idle trunk; and the principal object is the production of a new and improved pre-selecting trunk selecting switch of the above named type, that is, one that selects trunks ahead of the calls.

Another object is the production of a pre-selecting relay secondary switch that tests busy to the switches having access to it at all times except when it has an idle trunk actually pre-selected.

The above mentioned objects, together with such others as are not specifically mentioned at this time, will be pointed out more fully hereinafter, reference being had to the accompanying drawings comprising Figs. 1 and 2, in which Fig. 1 is a secondary trunking layout showing a typical situation in which the improved switch may be employed, while Fig. 2 shows by means of the usual circuit diagrams a sufficient amount of the apparatus used in connection with the improved switch to enable the invention to be thoroughly understood.

Referring now particularly to Fig. 1, this diagram shows an arrangement of primary and secondary trunks, whereby a group of first selector switches is given access on a particular level to a group of thirty second selector switches. The primary trunks, that is, the ones directly accessible to the first selectors, are divided into groups of ten, corresponding to the usual capacity of a selector switch on one level, and the division into groups is carried far enough to give the required ratio between the total number of primary trunks and the total number of secondary trunks, assumed in the present case to be the ratio of four to three. The first five trunks of each primary group, which are the ones which always become busy first, are taken direct to second selectors and do not pass through secondary switches. This is done under the assumption that when the traffic reaches the peak there will be at least five trunks busy out of every group of ten. The last five trunks accessible to each subgroup of first selectors or the last five

trunks of each primary group, are taken through secondary switches such as the secondary switch SS. Each of the secondary switches has access to two second selectors, which gives each first selector access, on the level in question, to any one of fifteen trunks instead of ten.

It will be understood, of course, that this trunking diagram presents nothing broadly new and that it is used merely to enable the utility of the improved secondary switch to be understood.

Referring now particularly to Fig. 2, the selector D shown therein is one of the sub-group which has access to the ten trunks shown in the upper left hand corner of Fig. 1. This switch is mechanically of the usual vertical and rotary type in which the bank contacts are arranged in horizontal rows or levels.

The secondary switch SS, which is accessible to the selector D, selects trunks by the operation of the relays 50 and 51 as will be hereinafter explained. This switch has access to the selectors E and E', denoted by the dotted rectangles bearing those reference characters. The selectors E and E', it will be understood are identical with the selector D. These selectors are accessible to three other secondary switches as can be seen in Fig. 1.

The apparatus, having been described in general, will now be described in connection with a detailed description of its operation. For this purpose it will be assumed that a call is extended to the selector D by way of the trunk comprising conductors 11, 12, and 13. When this occurs, line relay 14 energizes over the two sides of the calling line in series and closes a circuit for release relay 15 at armature 24. Release relay 15, upon energizing, prepares a circuit for stepping relay 17 and for switching relay 18 at armature 25, and at armature 26 opens a point in the circuit of release magnet 34 and prepares a circuit for vertical magnet 23.

In response to the calling of the first digit in the desired number, the circuit of line relay 14 is opened a corresponding number of times and, upon each deenergization of line relay 14, the following circuit is closed for vertical magnet 23: from ground by way of the resting contact 32 and said armature,

armature 24 and its resting contact, armature 26 and its working contact, relay 16, and vertical magnet 23 to battery. By the operation of vertical magnet 23, the wipers 34, 35, and 36, are raised step by step until they stand opposite the desired level of bank contacts, which level it will be assumed is the one in which the trunk extending to the secondary switch SS terminates. Relay 16 is energized in series with vertical magnet 23 and, being slow acting, retains its armature attracted throughout the vertical movement. Upon the closure of off normal contacts 19, a circuit is completed for stepping relay 17. Stepping relay 17, upon energizing, closes a locking circuit for itself at armature 28, and at armature 29 prepares a circuit for rotary magnet 21.

At the end of the vertical movement, relay 16 deenergizes, thereby closing a circuit for rotary magnet 21 by way of armature 29 and its working contact. Rotary magnet 21, upon energizing, advances its wipers 34, 35, and 36, into engagement with the first set of contacts in the level opposite where they are raised, at the same time opening the circuit of stepping relay 17. Stepping relay 17, upon deenergizing, opens the circuit of rotary magnet 21 at armature 29, and rotary magnet 21, upon deenergizing, closes its interrupter contacts 22 again. From this point, the operation depends upon whether the trunk terminating in the first set of contacts is busy or idle. If it is busy the test contact thereof is grounded and stepping relay 17 energizes again, whereupon the wipers are advanced into engagement with the next set of bank contacts by the energization of rotary magnet 21. This alternate operation of stepping relay 17 and rotary magnet 21 continues until an idle trunk is reached, which trunk it will be assumed is the one extending to the secondary switch SS. It will be assumed further that the selector E is idle at this time and, consequently, that relay 51 of the secondary switch SS is deenergized, as shown. With the assumption as noted, when the wipers 34-36, inclusive, arrive on the bank contacts 37-39, inclusive, switching relay 18, which heretofore has been short circuited by the ground potential which is present upon the test contacts passed over by test wiper 35, energizes in series with stepping relay 17. Stepping relay 17 does not energize at this time, however, on account of the high resistance of switching relay 18. Upon energizing, switching relay 18 removes ground from the armature of line relay 14 at armature 32; opens the test circuit and prepares the holding circuit at armature 31, thereby placing ground from the grounded release trunk conductor 12 upon the release trunk conductor of the secondary switch SS, so as to make the seized trunk busy imme-

dately to the other switches having access to it. This ground potential extends also by way of armature 56 and its resting contact to the release trunk conductor of the selector E, thereby rendering selector E busy to the other switches having access to it. The ground potential which is placed upon the release trunk conductor of the selector E extends by way of the resting contact of armature 52 and said armature to the upper winding of relay 51. Relay 51, however, being stiffly adjusted, does not energize immediately.

Returning now to the selector D, as a still further result of the energization of switching relay 18, it disconnects the incoming trunk conductors 11 and 13 from windings of line relay 14 and extends them by way of armatures 30 and 33 and their working contacts, wipers 34 and 36, bank contacts 37 and 39, the lower winding of line relay 50 of the secondary switch SS, and armatures 55 and 58 and their resting contacts to the upper and lower windings of the line relay (not shown) of the selector E. The line and release relays of the selector E, which relays correspond to the line and release relays 14 and 15 of the selector D, now energize and prepare the switch for operation in the usual manner.

In the secondary switch SS, line relay 50 energizes in series with the line relay of the selector E and, upon so doing, closes a locking circuit for itself at armature 53; opens the circuit of relay 51 at armature 52 before the said relay 51 has had time to energize, and at armature 54 cuts the lower line conductor straight through and opens its own winding. Armature 53 is adjusted to make contact with its working contact before armatures 52 and 54 operate. This insures that armature 54 does not short circuit the lower winding of relay 50 before the current begins to flow through the upper winding thereof.

The calling subscriber now dials the next digit in the desired number, whereupon the selector E operates in the usual manner to raise its wipers to the desired level and select an idle trunk. In response to the calling of the remaining digits in the desired number the connection is extended to the desired line in the usual manner.

When the receiver is replaced at the calling substation, the circuit of the line relay of the switch to which the connection has been extended is opened, whereupon the associated release relay deenergizes and opens the holding circuit of the selectors D and E and of the secondary switch SS. In the secondary switch SS relay 50 deenergizes in response to ground being removed from the associated release trunk conductor, thereby restoring conditions in this switch to normal. In the selector D, switching relay 18,

upon deenergizing, closes a circuit for release magnet 40 at armature 32, which circuit extends by way of armature 24 and its resting contact, armature 26 and its resting contact, and off normal contacts 20. Upon the energization of release magnet 40, the wipers 34-36, inclusive, are restored to normal position in the usual manner, the circuit of release magnet 40 being opened at off normal contacts 20 by the switch shaft when the latter reaches normal position. The selector E is restored to normal in the same manner.

Assuming now that the selector E is seized by a secondary switch other than the secondary switch SS, a ground potential is placed on the release trunk conductor of the switch E immediately upon the switch E being seized, as hereinbefore explained. This ground potential extends by way of the resting contact of armature 56 and said armature to the release trunk conductor of the secondary switch SS, thereby making the said secondary switch SS busy. This ground potential extends also by way of the resting contact of armature 52 and said armature to the upper winding of relay 51. Relay 51, upon energizing, prepares a locking circuit for itself at armature 57; transfers the release trunk conductor of the switch SS from the release trunk conductor of the switch E to the release trunk conductor of the switch E' at armature 56, thereby removing the busy potential from the release trunk conductor of the secondary switch SS, provided the selector E' is not busy; and at armatures 55 and 58 transfers the line conductors of the secondary switch SS from the line conductors of the selector E to the corresponding conductors of the selector E'.

As before stated, if the selector E' is idle the secondary switch SS is rendered idle again. If the secondary switch SS is not seized before the selector E becomes idle, relay 51 is then deenergized and the conductors of the switch SS are again connected with the conductors of the selector E. Assuming, however, that the switch SS is seized while the switch E is busy, relay 50 energizes in series with the line relay of the selector E and produces the circuit changes hereinbefore described. Also, relay 50, upon energizing, brings armature 59 into engagement with its working contact just before armature 52 breaks away from its resting contact, thereby closing a locking circuit for relay 51. The connection may now be completed to the desired line in the usual manner.

When the connection is released, ground is removed from the release trunk conductor of the selector E', whereupon relay 50 deenergizes; opens the locking circuit of relay 51 at armature 59; and connects the upper winding of the said relay 51 with the re-

lease trunk conductor of the selector E at armature 52. If the selector E is idle at this time, relay 51 deenergizes. However, if the selector E is busy, relay 51 remains energized and the selector E' remains pre-selected by the secondary switch SS. 70

The various features of the invention, having been described and ascertained in the foregoing, will be pointed out in the appended claims. 75

What is claimed is:

1. In a telephone system, an outgoing trunk line, an incoming trunk line connected therewith, another outgoing trunk line, a relay, and means for energizing said relay to disconnect said incoming trunk line from the first named outgoing trunk line and to connect it with said other outgoing trunk line responsive to the first mentioned outgoing trunk line becoming busy. 80

2. In a telephone system, an outgoing trunk line, an incoming trunk line connected therewith, another outgoing trunk line, a relay, means for energizing said relay to disconnect said incoming trunk line from the first named outgoing trunk line and to connect it with said other outgoing trunk line responsive to the first mentioned outgoing trunk line becoming busy, and means for preventing the energization of said relay when said first outgoing trunk line becomes busy due to seizure by way of said incoming trunk line. 90

3. In a telephone system, an outgoing trunk line, an incoming trunk line connected therewith, another outgoing trunk line, a relay, means for energizing said relay to disconnect said incoming trunk line from the first named outgoing trunk line and to connect it with said other outgoing trunk line responsive to the first mentioned outgoing trunk line becoming busy, and means for maintaining said relay energized independent of the busy or idle condition of the first mentioned outgoing trunk line when said other outgoing trunk line is seized by way of said incoming trunk line. 100

4. In a telephone system, a trunk line having two branches, one normally connected and the other normally disconnected, a second trunk line similarly associated with said branches, and a relay in said first trunk line for disconnecting the first branch and for connecting the second branch whenever the first branch is in use in a connection established over said second trunk line. 115

5. In a telephone system, a trunk line having two branches, one normally connected and the other normally disconnected, a test conductor for said trunk line and for each branch, and a relay in said trunk line energized over the test conductor of the normally connected branch for disconnecting such test conductor from the test conductor associated with the said trunk line 120

and for connecting the last named test conductor with the test conductor associated with the normally disconnected branch.

6. In a telephone system, a trunk line having two branches, one normally connected and the other normally disconnected, a relay energized over a conductor of the normally connected branch for shifting the talking conductors of said trunk line from connection with the normally connected branch into connection with the normally disconnected branch, a local circuit for maintaining said relay energized, and a second relay energized over a conductor of said normally disconnected branch for closing said local circuit.

7. The combination, with an incoming line and a selecting device in which said line terminates, of a plurality of trunk lines accessible to said selecting device, and means in said selecting device consisting solely of relays and circuit connections therefor, for maintaining said incoming line normally in connection with an idle one of said trunk lines.

8. The combination, with an incoming trunk line and a selecting device in which said trunk line terminates, of a plurality of outgoing trunk lines accessible to said selecting device, said incoming trunk line being normally connected to one of said outgoing trunk lines, and a relay for connecting the incoming trunk line with an outgoing trunk line other than said normally connected line whenever the normally connected outgoing trunk line becomes busy due to being seized independent of said device.

9. The combination, with an incoming line and a selecting device in which said incoming line terminates, said selecting device consisting solely of two relays and circuit connections therefor, of two outgoing lines one of which is normally connected to the incoming line, and circuit connections for energizing only one of said relays when a connection is extended over the incoming line and the normally connected outgoing line, and for energizing both relays to extend a connection over the incoming line and the other outgoing line.

10. In a trunking system, a plurality of incoming lines each terminating in a selecting device, a group of trunk lines accessible to said selecting devices in common, one of said trunk lines being normally connected to each incoming line at its associated selecting device, a relay in each selecting device, and circuit connections effective when a connection is extended over an incoming line and the normally connected trunk line for energizing the said relays in the selecting

devices associated with the other incoming lines to connect such incoming lines with one of said trunk lines other than the normally connected line.

11. In a telephone system, two outgoing trunks, a plurality of incoming trunks any one of which may seize either of the two outgoing trunks, each of the incoming trunks including a relay arranged to connect it with one of the outgoing trunks when released and with the other when operated, means for operating each one of the said relays when the outgoing trunk to which it connects when released is seized by any incoming trunk other than the incoming trunk with which such relay is associated, and means for maintaining one of said relays operated when its incoming trunk seizes the second outgoing trunk.

12. In a telephone system, an incoming trunk, two outgoing trunks, a relay arranged to connect said incoming trunk with one of said outgoing trunks when operated and with the other when released, a release conductor in each of said trunks, a second relay, an operating circuit for said first relay controlled by a back contact on the last named relay and the release conductor of an outgoing trunk, another circuit for said first named relay controlled by front contacts on each of said relays, and a circuit for said second named relay established when said incoming trunk is seized.

13. In a telephone system, a trunk having an incoming section and two outgoing sections, a relay associating said incoming section with one of said outgoing sections in one position and with the other section in another position, means establishing an operating and holding circuit for said relay when the first mentioned outgoing section becomes busy while the incoming section is idle, and means for establishing another holding circuit for said relay and opening said operating circuit if said incoming trunk subsequently becomes busy.

14. In a telephone system, a trunk having an incoming section and two outgoing sections, a relay associating said incoming section with one of said outgoing sections when operated and with the other when released, means for operating said relay under predetermined conditions, and means operated when the incoming trunk is seized to prevent the operation of the relay if it has not already operated and to establish a holding circuit for said relay if it has already operated.

In witness whereof, I hereunto subscribe my name this 9th day of June, A. D. 1922.

CARL J. PRACHT.
